HOLD-DOWN FOR SPRING RAIL FROGS

John C. Gerlach, Tomah, Wis.

Application February 25, 1937, Serial No. 127,587

1 Claim. (Cl. 246—276)

The invention relates to hold-down devices for the movable rail of a spring railway frog.

Its object is to secure greater strength and reliability than it has been possible to attain in devices of this character heretofore used.

The improved hold-down is fully hereinafter described, and is illustrated in the accompanying drawing, in which

Fig. 1 is a detail plan of a spring rail frog;
0 Fig. 2 is a detail plan view of the hold-down and tie plate with which it is associated;

Fig. 3 is a sectional view on the line 3—3 of Fig. 2; and

Fig. 4 is a side elevation of the device, applied 5 to a tie plate, the horn of the reinforcing bar of the movable wing rail of the frog being indicated in dotted lines.

The hold-down device is shown at 5 in Fig. 1, associated with other elements of the frog of known form, comprising a pair of wing rails 10 and 11, one of which, 11, is laterally movable, and a fixed point 12. The housing of the spring for holding the wing rail 11 in normal position is conventionally shown at 13, and the reinforcing 10 bar riveted to the web of this rail is shown in dotted lines at 14.

The tie plates associated with the frog are designated 15; the holes for the spikes for attaching these plates to the ties are represented 15 at 16; limiting stops for arresting the lateral movement of the movable wing rail are represented at 17, 18, one of them taking the form of a spring device. The bar 14 is provided with a laterally projecting horn 19, for cooperating with the hold down element.

The body portion of the hold-down, generally designated by the numeral 21, is of the usual shape, having the form of an inverted U, formed of heavy sheet metal and being secured to a tie plate 15. This body portion is open at its ends, one of which is directed toward the wing rail 11, and the vertical height of its chamber is but slightly greater than the vertical dimension of the horn 19.

Portions of the side walls 22, 23, of this hold-down element are prolonged downwardly and project through individual slots 24, 25, in the tie plate 15, and are bent laterally, as shown at 26, 27, to engage the lower face of this plate. The slotted portion of the tie plate is offset upwardly, as shown at 28, to provide space for the lateral extensions 26, 27.

The hold-down is secured to the tie plate be-

fore the latter is attached to the frog. The feet portions 26, 27, when inserted in the plate apertures, are straight and are heated previous to their insertion. After they are inserted they are bent laterally to bear against the lower face of the tie plate to which they are then welded. The width of the feet 26, 27, is preferably less than the length of the body of the hold-down, and the feet are shown as being located adjacent to the outer end of the body. A bar 29 extends transversely of the tie plate, between the attaching feet and the forward end of the hold-down, and serves the double purpose of a limiting stop for arresting the lateral movement of the movable wing rail and as a bearing for the horn 19.

As heretofore made hold-down devices have been secured to the tie plate by bolts which, however securely locked, become loosened by the vibration incident to the heavy service, thereby permitting vertical movement of the wing rail and consequent injury thereto as the ends of the rail are apt to be bent upwardly unless the hold-down device functions efficiently.

The construction as shown insures permanent rigid attachment of the hold-down to the tie plate; the parts are easily assembled and permanently secured together, and there is practically no weakening of the tie plate.

I claim as my invention:—

In a hold-down device for spring rail frogs comprising in combination, a tie plate having its central portion offset upwardly forming upwardly projecting parallel bends extending at an angle to an end edge of the plate, said plate being provided with two parallel slots between said bends extending at an acute angle to a side edge of said plate, a U-shaped metal loop having its ends reduced in width and projecting through said slots and having its projecting ends bent outwardly in opposite directions in engagement with the lower surface of said offset portion and extending at substantially right angles to said bends and welded thereto by weld metal in pockets formed between the edges of the projecting ends and the adjacent bends of the plate, said slots being of a length and width but slightly greater than the width and thickness of the ends of said metal loop, and a bearing and stop bar rigidly secured to the upper surface of said plate inwardly of the innermost bend and parallel therewith, said loop extending over said bar.

JOHN C. GERLACH.
